United States Patent Office

Des. 224,879
Patented Oct. 3, 1972

224,879

SHEET OR SIMILAR ARTICLE OF BED LINEN

Leonard C. Clementi, Huntington, N.Y., assignor to Cannon Mills Company, Kannapolis, N.C.

Filed Feb. 19, 1971, Ser. No. 117,212

Term of patent 14 years

Int. Cl. D6—13

U.S. Cl. D6—264

FIG. 2

FIG. 1 is a top plan view of a sheet or similar article showing my new design, a design unit being shown within the broken lines, which unit repeats in regular succession beyond the unit boundaries; and

FIG. 2 is an enlarged top plan view of the design unit. I claim:

The ornamental design for a sheet or similar article of bed linen, substantially as shown and described.
